DESIGN FOR A COMBINED GARMENT HANGER AND DOOR PULL OR SIMILAR ARTICLE

Ansel Dailey, Parkersburg, W. Va.

Application September 20, 1943, Serial No. 111,164

Term of patent 14 years

To all whom it may concern:

Be it known that I, Ansel Dailey, a citizen of the United States, residing at Parkersburg, in the county of Wood and State of West Virginia, have invented a new, original, and ornamental Design for a Combined Garment Hanger and Door Pull, or Similar Article, of which the following is a specification, reference being had to the accompanying drawing, forming part thereof.

Figure 1 is a view in side elevation of a combined garment hanger and door pull, or similar article, embodying my new design;

Figure 2 is a view in front elevation; and
Figure 3 is a view in top plan.

I claim:

The ornamental design for a combined garment hanger and door pull, or similar article, as shown.

ANSEL DAILEY.
